UNITED STATES PATENT OFFICE.

CARL O. WOLD, OF MINNEAPOLIS, MINNESOTA.

CUTTING SECTION FOR ROAD-SCRAPER BLADES.

Application filed July 15, 1926. Serial No. 122,527.

This invention relates to improvements in the renewable cutting sections or edges of road scraper blades.

The object of the invention is to provide 5 a cutting section of the type specified having a stiff and firm edge portion that will not vibrate or chatter as the scraper is drawn or passed over a road surface, which may be more or less uneven and which will often 10 have small stones or loose gravel scattered thereon, and formed integrally therewith is a thinner broad plate portion adapted to fit against the front surface of the lower part of a scrap mold board and to be rigidly secured 15 thereto.

A particular object of the invention is to provide such a cutting section that can be produced from a billet of proper dimensions at a single operation by passing the billet 20 between suitable rolls.

The invention consists generally in the constructions and combinations hereinafter described and particularly pointed out in the claims.

25 In the accompanying drawings forming part of this specification,

Figure 1 is a transverse sectional view of a cutting section embodying my invention and illustrating the application of the cutting section to a mold board;

30 Figure 2 is a front elevation of the section.

In the drawing, 2 represents the lower or cutting portion of the section and 3, the 35 upper or plate portion by which, when in use, the section may be firmly secured upon the front of the mold board.

The full front of the section (both portion 2 and portion 3) is preferably con- 40 caved or curved from its lower to its upper edge—preferably upon substantially a 12" radius. The portion 2 of the section is pro- 45 vided at its lower front face with a cutting edge 4, and the lower face 5 of the section is flat and smooth and is formed to rest upon the surface of the road as the scraper is moved over such surface.

The upper or plate portion 3 of the section has its front surface forming a contin- 50 uation of the curved face of the portion 2 of the section. The plate portion 3 is pref- erably of about one-half the thickness of the lower portion, a shoulder 6 being formed at

the rear of the portion 3 and the top of the portion 2.

The two surfaces—the top of portion 2 and the rear of portion 3—are united by the curved surface 7. The upper edge of the portion 3 is also preferably curved or round- 55 ed off at 8 as shown.

The portion 2 of the section projecting downwardly and rearwardly from the portion 3, and of about twice its thickness, is sufficiently stiff and rigid to prevent vibra- 60 tion or chattering and the broad flat surface of the upper portion permits of a firm and rigid connection to the mold board. The lower edge of the portion 2 also forms a thick wearing surface to contact with the 65 surface of the road.

The upper portion 3 of the section is re- 70 duced in thickness, and fits the ordinary offset in the mold board.

The use of this portion of reduced thick- 75 ness results in making the section easier to handle and saves considerable material over what would be required if the section was of the same thickness throughout.

This section not only possesses the struc- 80 tural advantages pointed out but it may be rolled at a single operation by passing a billet of the required dimensions between suitable rolls.

I claim as my invention:

1. A scraper blade cutting section formed 85 integrally and comprising a lower portion having a flat wearing surface of substan- tial area adapted to rest, when in use, upon the road surface, with a cutting edge at the front of the wearing surface, an upwardly 90 extending plate portion of reduced thickness having its forward surface forming with the forward surface of the lower portion an unobstructed curved face over which material may freely pass, and the rear sur- 95 face of the upper portion providing an offset with the rear surface of the lower portion, the whole forming a structure capable of being produced at a single operation by passing a billet of requisite dimensions be- 100 tween suitable rolls.

2. A scraper blade cutting section formed integrally and comprising a lower portion having a flat wearing surface of substantial area adapted to rest, when in use, upon the road surface, with a cutting edge at the front 105

of the wearing surface, an upwardly extending plate portion of reduced thickness having its forward surface forming with the forward surface of the lower portion an unobstructed curved face over which material may freely pass, and the rear surface of the upper portion providing an offset with the

rear surface of the lower portion, and adapting said section to be firmly secured to the lower edge of a mold board.

In witness whereof, I have hereunto set my hand this 9th day of July 1926.

CARL O. WOLD.
